UNITED STATES PATENT OFFICE.

CHARLES DE LUKACSEVICS, OF NEW YORK, N. Y.

DESIGN FOR A SIPHON-HEAD.

41,432.

Specification for Design.

Patented June 6, 1911.

Application filed March 20, 1911. Serial No. 615,797. Term of patent 3½ years.

To all whom it may concern:

Be it known that I, CHARLES DE LUKACSEVICS, a citizen of the United States of America, residing at the city of New York, in the county and State of New York, have invented a new, original, and ornamental Design for Siphon-Heads, of which the following is a specification, reference being had to the accompanying drawing, forming part thereof, in which—

Figure 1 is a view in elevation of a siphon

head embodying my design; and Fig. 2 is a view in elevation taken at right angles to Fig. 1.

I claim:

The ornamental design for a siphon head, as shown.

CHARLES DE LUKACSEVICS.

Witnesses:

B. B. ZIPPERT,
A. MITTLER.
